SUPPORT FOR BOOTS OR THE LIKE

Charles E. Montague, Syracuse, N. Y.

Application July 29, 1939, Serial No. 287,426

8 Claims. (Cl. 12—129.1)

This invention relates to supports for boots or the like and more particularly to supports especially adapted for holding such articles while being dried.

When drying boots, shoes and the like it is desirable to hold the article in a shape or form approximately the same as its shape or form when in use. This not only provides for better circulation of air and more rapid and even drying, but leaves the dried boot or shoe approximately in its normal shape, thus obviating the necessity of the wearer's forcing the foot into a stiff, distorted foot-covering with accompanying rapid wear on the lining and sometimes resulting in tearing of the top.

An object of the present invention is to provide an improved support of the character referred to which is adapted to support a boot or the like in a position most conducive to rapid uniform drying in a shape approximately the shape when in use.

Another object is to provide such a support which is adapted to hold the top of the boot or shoe leg open to permit circulation of air within the boot or shoe.

Another object is to provide a support of the character referred to which may easily and quickly be assembled and taken apart for packing and carrying in a car, grip, pack basket, or camper's duffle bag.

A further object is to provide such a support constructed and arranged to permit adjustment to fit boots or the like of various sizes. Other objects will be apparent from a reading of the following description, the appended claims and the accompanying drawing, in which:

Figure 1 is a perspective view of a support embodying the invention;

Fig. 2 is a perspective view of the support as applied to a boot;

Figure 3 is a section taken transversely through the leg part of the boot shown in Figure 2 and looking toward the open or top end thereof; and

Figure 4 is an elevation showing a boot held on the support and the latter suspended from a wall.

In its general nature, the support S shown for the purposes of illustration includes an extensible foot part F adapted to lie parallel to the foot F' of a boot B, an extensible leg part L having a portion adapted to lie parallel to and behind the boot leg L', and a spreader part s adapted to extend down into the boot leg, and to contact a substantial part of the inner circumference thereof for maintaining the boot leg open to permit circulation of air within the entire boot. In its preferred form, the

support is arranged to be taken apart and assembled and to be adjustable to fit boots of different sizes.

The leg part L is shown as comprising two L-shaped tubular members 1—1 each having a portion 2 adapted to extend parallel to and behind the boot leg L' and a portion 3 adapted to lie parallel to the boot heel 3'. In the assembled support, the leg members 1—1 are spaced from each other and connected together by the foot part F and spreader s as will be described.

The foot part F is U-shaped and has its free ends 4—4 received telescopically respectively in the heel portions 3—3 of the leg part L. The part F is resilient and the arrangement is such as to permit sliding of the ends 4—4 in and out of the heel portions 3—3 to adjust the support to different boot foot sizes.

The spreader s is positioned at the end of the leg part remote from the foot part. It includes two shanks 5—5 received telescopically respectively in the ends of the tubular portions 2—2, the shanks forming extensions of the leg parts 2—2. Remote from its connection to the associated leg part 2, each shank merges with a turned-in part 6 extending transversely of the leg part and inwardly over the foot part. The transverse portion 6 then merges with a part 7 extending longitudinally of the leg part and toward the foot part. The two return-extending parts 7 are connected by a loop 8 disposed generally in a plane parallel to the plane of the foot part F and adapted to contact a substantial part of the inner circumference of the leg of a supported boot.

Preferably, the foot part F and spreader s are formed of resilient wire. This facilitates adjustment. A V-shaped reinforcing or stiffening member R, also formed of wire is arranged to have sliding connection as at 9—9 with the leg parts 2.

In order to apply the support S to a boot such as the boot B, the parts F, L and s are assembled as shown in Figure 1, the foot part F being adjusted to a length a little less than that of the boot foot F', and the spreader s is positioned in accordance with the length of the boot leg L'. When the support is applied to the boot, the loop 8 of the spreader should be positioned down inside the boot leg. In some cases it may be advantageous to pull the spreader outwardly before setting the boot in the support, and then, after the boot leg is disposed along the leg parts 2, to push the spreader back toward the foot part F until the loop 8 is in the desired position. A lacing 10 may be extended over the boot toe 55

- and secured to the foot part F to assist in holding the boot foot in an upright position, thus preventing the boot foot from dropping laterally and twisting the boot leg.
5. When it is desired to suspend the boot in inverted position, an additional lacing 11 may be extended over the boot instep I and secured to the stiffening member R. The support and boot may then be suspended from a nail, hook or the like 12 driven in a wall W and received in the reinforcing member R.
10. Supports embodying my invention preferably are adjustable to accommodate boots differing in size within rather wide limits. It will be apparent however that the leg parts L may be made in different lengths and the spreader s of different diameters in order to adapt the support for use in connection with three-quarter, half, or other length top boots.
15. 20. A support constructed in accordance with my invention, and exemplified by the preferred form disclosed herein, is of light, simple and inexpensive construction, it may readily be adjusted for use with boots or shoes of different sizes and styles, it may easily be assembled and taken apart, and is capable of maintaining a boot, shoe or the like in the shape and position most conducive to rapid and uniform drying. The support disclosed herein embodies the invention in 25 its preferred form but it will be understood that changes may be made without departing from the invention as defined in the claims.

I claim:

30. 35. 1. In a support for a boot or the like, a boot foot parallelling portion; a boot leg parallelling portion; and a boot leg spreader portion at the end of the leg parallelling portion which is opposite the boot foot parallelling portion, said spreader portion being extended transversely to 40 the leg parallelling portion over the foot parallelling portion and toward the latter portion.
2. In a support for a boot or the like, means for engaging the exteriors of and supporting a boot foot and leg; and means for extending from 45 the outside of the boot leg over the upper edge thereof and into the boot leg, said last named means including a spreader adapted to contact a substantial part of the boot leg inner circumference for holding the upper end of the boot leg open.
3. In a support for a boot or the like, means for engaging the exteriors of and supporting a boot foot and leg; and means for extending from the outside of the boot leg over the upper edge 55 thereof and into the boot leg, said last named means including a looped wire spreader adapted to contact a substantial part of the boot leg inner circumference for holding the upper end of the boot leg open.
4. In a support for a boot or the like, means for engaging and supporting a boot foot and leg including an extensible part adapted to lie longitudinally of the boot leg; and a spreader on

said extensible part and connected to that end thereof which is adapted to lie adjacent the top end of a boot leg, said spreader extending laterally of said extensible part to cross over a boot leg top and thence longitudinally toward the opposite end of the extensible part.

5. In a support for a boot or the like, a tubular part including a leg portion adapted to extend longitudinally of a boot leg and a heel portion at an angle to the leg portion and adapted to 10 extend under the boot heel; a foot part telescopically adjustably received in said heel portion and adapted to extend under the boot foot; and a member including a shank telescopically 15 adjustably received in said leg portion, a turned-in portion adapted to extend inwardly over the top of the boot leg, a return-extending portion adapted to project down into the boot leg, and a spreader portion carried by the return-extending portion.

6. In a support for a boot or the like, a tubular part including a leg portion adapted to extend longitudinally of a boot leg and a heel portion at an angle to the leg portion and adapted to 20 extend under the boot heel; a foot part telescopically adjustably received in said heel portion and adapted to extend under the boot foot; means connected to the foot part and adapted to embrace the boot toe; and a member including a shank telescopically 25 adjustably received in said leg portion, a turned-in portion adapted to extend inwardly over the top of the boot leg, a return-extending portion adapted to project down into the boot leg, and a spreader portion carried by the return-extending portion.

7. In a support for a boot or the like, a pair of substantially L-shaped tubular parts each including a leg portion adapted to extend longitudinally of a boot leg and a heel portion adapted to extend under the boot heel; a substantially 40 U-shaped foot part whose free ends respectively are telescopically adjustably received in said heel portions; and a member including two shanks respectively received telescopically and adjustably in said leg portions, said shanks 45 each being returned upon itself and the returned shank portions being connected by a loop adapted to fit around the inside of the boot leg.

8. In a support for a boot or the like, a U-shaped foot part adapted to extend under the 50 foot of a boot with the curved portion of the U at the boot toe, a leg part comprising spaced members adapted to lie adjacent and extend longitudinally of the boot leg and being connected at one end of each respectively to the 55 spaced arm portions of the U-shaped foot part; a spreader connected to the other ends of said spaced leg members and being adapted to extend into the top of the boot leg; and a stiffening member having sliding connection with said 60 spaced leg members adjacent their connection to the foot member.

CHARLES E. MONTAGUE.
